[57] CLAIM

The ornamental design for a packaging container, as shown and described.

DESCRIPTION

FIG. 1 is a right side view of a packaging container showing my new design, the left side is a mirror image thereof;

FIG. 2 is a top, right side perspective view thereof;

FIG. 3 is a top plan view thereof;

FIG. 4 is a bottom front perspective view thereof;

FIG. 5 is a bottom rear perspective view thereof;
FIG. 6 is a right side view of a second embodiment of the packaging container, the left side is a mirror image thereto;

FIG. 7 is a top right side perspective view of the second embodiment;

FIG. 8 is a top plan view of the second embodiment;

FIG. 9 is a bottom front perspective view of the second embodiment; and

FIG. 10 is a bottom perspective view of the second embodiment.

FIG. 1

FIG. 2

FIG. 3

FIG. 4

FIG. 5

FIG. 6

FIG. 7

FIG. 8

FIG. 9

FIG. 10
